UNITED STATES PATENT OFFICE.

FRANK W. MIX, OF STAMFORD, CONNECTICUT, ASSIGNOR TO THE YALE & TOWNE MANUFACTURING COMPANY, OF SAME PLACE.

BOLT FOR LOCKS.

SPECIFICATION forming part of Letters Patent No. 608,784, dated August 9, 1898.

Application filed November 16, 1897. Serial No. 658,759. (No model.)

To all whom it may concern:

Be it known that I, FRANK W. MIX, a citizen of the United States, and a resident of Stamford, in the county of Fairfield and State 5 of Connecticut, have invented certain new and useful Improvements in Bolts for Locks, of which the following is a specification.

In the better class of locks the trade demands that exposed portions of door-fittings 10 shall be of bronze or other materials more expensive than those used in the construction of the case and interior parts of the lock. To construct an entire bolt of bronze would be too expensive, and the tail of the bolt would 15 not be strong enough to give the service required of it, for it is required that locks be made as thin as possible and the tails of bolts should be made of flat metal. It is also desirable to make the parts of stamped metal. 20 My invention meets the requirements by providing a flat metal tail, of steel or equivalent metal, and a built-up head, of bronze or other metal, thereon, tenon-jointed thereto, preferably by having the end of the tailpiece 25 engage with one of the component parts of the head, while the joint is completely covered and obscured by the other part or parts thereof.

In carrying out my invention I preferably shape or cut out the end of the tailpiece and 30 the adjacent edge of one lamina of the built-up head to form a tenon-joint or so that these parts will engage laterally and hold together against displacement, and I then apply to the sides of these interlocked parts overlapping 35 plates, of bronze or other metal. The component plates of the head correspond in outline to the vertical section of the bolt-head and are sufficient in number to build up the head to the desired size. In practice I prefer to 40 dovetail or otherwise form the interengaging parts of the tail and head, so that they will also interlock against longitudinal displacement.

My invention will be fully understood upon 45 reference to the accompanying drawings, in which—

Figure 1 is a perspective view of a complete bolt constructed in accordance with my invention. Fig. 2 is a perspective view of the 50 segregated parts of the bolt, showing a form of engaging parts wherein they interlock.

Fig. 3 is a similar view showing another form of engaging parts.

1 represents the tail of the bolt, and 2 the head, which is made up of a number of laminae or plates corresponding in outline to the vertical section of the bolt, the number being determined by the size or thickness of which it is desired to have the bolt. In forming the bolt I cut out or shape the outer end as shown 55 at 1^a in Fig. 2 or as at 1^a in Fig. 3 and a corresponding recess 1^b or 1^b in the central plate or lamina 2^a, which is to form part of the head. These parts are then fitted together, and additional plates or laminae 2^b are applied 60 on opposite sides in such a manner as to overlap the interengaging parts 1^a and 2^a or 1^a and 2^a. Perforations 4 5 are drilled in the parts in the proper positions, and into these perforations pins or rivets 3 are introduced, 65 so as to hold all the parts together to form a solid head. The head may then be trimmed or finished.

The form of joint shown in Fig. 2 provides for interlocking of the parts both laterally 75 and longitudinally, while the form shown in Fig. 3 simply provides for lateral engagement; but in the latter form the rivets are entirely sufficient to hold the parts securely against longitudinal disengagement. 80

Inasmuch as the plates or laminae 2^a 2^b are of bronze or other metal suitable to form the exposed portion of the bolt and the engaging end of the tailpiece 1 is completely obscured by them, it will be seen that I have provided 85 a bolt of cheap, durable, and attractive appearance, of which the head or portion exposed to view is practically formed of solid bronze or other ornamental metal with all the wearing qualities thereof, while the tailpiece 90 is of steel and embodies all the advantages of cheapness, strength, and durability required of that portion of the bolt.

I do not herein claim anything disclosed by the application of Warren H. Taylor, filed 95 October 4, 1897, Serial No. 654,080.

Having thus described my invention, the following is what I claim as new therein and desire to secure by Letters Patent:

1. A bolt comprising a tailpiece formed 100 with a tenon and a separately-formed head secured thereto and consisting of a series of

plates or laminae, one of which is partly cut away to receive the tenon formed on the end of the tailpiece whereby the head and the tailpiece engage together, as explained.

5 2. A bolt formed of a tailpiece, a head-forming plate engaging said tailpiece, a lateral head-forming plate covering the joint between the two parts first named, and rivets passing through the outer plate and the tailpiece and 10 through the head-forming plates, substantially as set forth.

3. A bolt comprising a tailpiece and a built-up or laminated head secured thereto; the end of the tailpiece and one of the plates or

15 laminae of the head being constructed to interlock by a substantially dovetailed joint,

whereby lateral and longitudinal displacement are prevented, as explained.

4. A bolt consisting of a steel or hard-metal tailpiece and a soft-metal or ornamental head composed of plates or laminae of which the inner plate or lamina and the end of the tailpiece are correspondingly recessed to form a tenoned joint, while the outer plates or laminae are arranged to obscure said joint, and all of 20 said parts being secured together by rivets or pins passing through them, substantially as and for the purposes set forth.

FRANK W. MIX.
